DERAILING FROG

Filed Nov. 29, 1929

Fig. 1.

UNITED STATES PATENT OFFICE

CHARLES BESS, OF DUNSMUIR, CALIFORNIA

DERAILING FROG

Application filed November 29, 1929. Serial No. 410,344.

This invention relates to derailing frogs, and is designed for the purpose of derailing the wheels of locomotives or tenders, if, when left unattended at engine houses or on lead tracks, they should move on account of grade, defect in locomotive, or for any other reason. By placing these frogs behind and in front of the locomotive and tender, derailment will follow movement in either direction; said frogs thus serving as a precaution against accident or serious damage to equipment and property, as would be the case if said movement were not arrested. The present derailing frog is fashioned to overlie and rest upon the rail-head, and is formed with legs to avoid tipping when placed in position; side shoulders to avoid lateral shifting under functional stress; a toe-plate to prevent slipping under the stress of the entering wheel; a tread surface for raising the entered and advancing wheel to a height at which the bearing is transferred from the wheel tread to the wheel flange; and a derailing member acting against the side of the flange to sidle the wheel clear of the frog and rail.

In the accompanying drawings, the preferred form of the device is illustrated, though it is to be understood that changes may be made without departing from the spirit of the invention as defined by the claims hereunto appended.

In these drawings:—

Fig. 1 is a top plan view of the derailing frog.

Fig. 2 is a side view of the same.

Fig. 3 is a cross section on the line 3—3 of Fig. 1.

Fig. 4 is a cross section on the line 4—4 of Fig. 1.

1 is a rail of the ordinary T-type, 2 is a cross tie, and 3 is a spike securing the rail to the tie. 4 indicates a wheel of the vehicle upon which the derailment is to be effected.

The body of the frog 5 is, in practice, made of cast steel. To its entering end is welded and projects a flat iron toe-plate 6, which lies upon the head of the rail 1 and has a beveled front edge 7. The under surface of the body 5 rests upon the head of the rail 1, and is retained thereupon by opposite depending

shoulders 8 and 9. From the inside of the body 5, a pair of legs 10 extend downwardly with a length sufficient to rest upon the rail base.

The upper surface of the body 5 from its forward end 11 where it merges into the level of the flat toe-plate 6, gradually rises to a maximum height at 12, about midway of its length, and then drops again to a lower level 13, as shown in Fig. 2. On the leg side or inside of the frog is formed the derailing member 14 which is an upstanding flange springing outwardly from its union with the body of the frog, and separated from said body by a groove 15 deep enough at its beginning to receive the flange of the entering wheel 4, as shown in Fig. 3, said groove thence riding to and merging into the level of the upper or tread surface of the body at its low point 13. The derailing flange 14 gradually converges to and partially crosses the end of the body, as shown in Figs. 2 and 3.

The purpose of the flat toe-plate 6 is to prevent the frog from slipping as the wheel enters and encounters the rise. The legs 10 rest upon top of the rail-base and prevent the frog from tipping off the rail. They also prevent it from shifting along the rail as the wheel ascends its point; and by placing their feet against a spike 3 driven into the tie, as shown in Figs. 1 and 2, this effect is further insured. The legs may be designed to suit the height of the rail. The retaining shoulders 8 and 9 prevent the frog from slipping sideways, and insure its central position upon the rail. The width between these shoulders may be suited to that of the rail head. As the locomotive or tender starts to move, the tread of its wheel 4 runs upon the beveled end of the toe-plate 6 and holds the frog from slipping as it encounters the rise of the body 5. Upon this rise the wheel tread rolls and is lifted until the wheel flange is even with or above the level of the groove 15. Into said groove the wheel flange now enters, and as the groove rises and the body tread-surface drops, the wheel is borne upon its flange, until, by reason of the converging derailing flange 14, said wheel is sidled off the frog toward the outside and derailment is accomplished.

The body 5, derailing flange 14, and legs 10, are preferably cast integrally. The underside of the body may be formed with cavities 16, if desired, to save metal and prevent unnecessary weight.

5 I claim:—

1. A derailing frog fashioned to rest upon the head of a rail, said frog having at its forward end a projecting flat toe-plate to receive 10 the entering wheel and prevent the frog from slipping, said frog having a rising tread surface to lift the wheel rolling thereon and a groove to receive the wheel flange, said tread surface and said groove merging into substantially the same horizontal plane, and a derailing flange converging to and crossing the tread surface to sidle the wheel therefrom.

2. A derailing frog fashioned to rest upon the head of a rail and having legs to rest upon 20 the rail base to prevent tipping, said frog having at its forward end a projecting flat toe-plate to receive the entering wheel and prevent the frog from slipping, and said frog having a rising tread surface to lift the wheel and 25 a groove to receive the wheel flange, said tread surface and said groove merging into substantially the same horizontal plane, and a derailing flange converging to and cross the tread surface to sidle the wheel therefrom.

30 In testimony whereof I have signed my name to this specification.

CHARLES BESS.
